Primary Examiner — Janice Hallmark(74) *Attorney, Agent, or Firm* — Gottlieb, Rackman & Reisman, PC(57) **CLAIM**

The ornamental design for a device car mount, as shown and described.

DESCRIPTION

FIG. 1 is a front perspective view of a device car mount showing my new design;

FIG. 2 is a first side perspective view thereof;

FIG. 3 is a second side perspective view thereof;

FIG. 4 is a first side elevation view thereof;

FIG. 5 is a second side elevation view thereof;

FIG. 6 is a front elevation view thereof;

FIG. 7 is a rear elevation view thereof; and,

FIG. 8 is a top perspective view thereof.

The broken lines shown in the drawings are included for the purpose of illustrating portions of the article that form no part of the claimed design.

1 Claim, 8 Drawing Sheets(56)
